UNITED STATES PATENT OFFICE.

JAMES ERNEST JOHNSON, OF BOLTON, ENGLAND, ASSIGNOR TO HICK, HARGREAVES & COMPANY LIMITED, OF BOLTON, ENGLAND.

STEAM CONDENSER, FEED-WATER HEATER, AND THE LIKE.

Application filed July 3, 1922. Serial No. 572,684.

To all whom it may concern:

Be it known that I, JAMES ERNEST JOHNSON, a subject of the King of Great Britain and Ireland, and residing at Soho Iron Works, Bolton, in the county of Lancaster, England, have invented certain new and useful Improvements in and Relating to Steam Condensers, Feed-Water Heaters, and the like, of which the following is a specification.

This invention relates to doors or end closure means for steam condenser, feed heater and the like units and has for its object the provision of means for facilitating the opening and closing of the door or end closure of a condenser or feed heater.

The invention is particularly applicable to that type of condenser or feed heater having end boxes comprising two parts and in which the end closure is divided adjacent the centre line or diameter forming two parts or doors which are hinged and adapted to open outwardly.

Doors of this type are usually used in connection with surface condensers using dirty water for circulating purposes, this construction enabling one half of the condenser tubes to be cleaned without entirely shutting the machine down.

The invention consists in providing means whereby the door is capable of displacement in relation to the condenser or other fixed seating. This displacement it will be understood is separate and distinct from the usual partial rotary movement of the doors about their hinges or pivots and is a supplementary movement.

This effect may be attained by displacing the pin upon which the door is hinged with reference to the seating of the door or by displacing the door with reference to the axis of a fixed hinge pin and with respect to the seating of the door, or a fixed hinge pin may be employed and means provided which is adapted to displace the axis about which the door hinges in opening or closing.

Further features of the invention will be hereinafter described and defined in the claims.

In the accompanying drawings:

Figure 1 is a front elevation showing a condenser having a pair of doors mounted and arranged according to one form of the present invention.

Figure 2 is an enlarged plan of Figure 1.

Figure 3 is an enlarged cross-sectional elevation of the upper hinge for the doors as shown in Figure 1.

Figure 4 is an enlarged section showing the slots and studs for securing the inner sides of the doors to their seating shown in Figure 1.

In carrying the invention into effect according to one convenient mode as applied to a condenser of circular cross-section, the end closure is divided upon the vertical diameter forming two doors 1 and 2, either of which may be opened independently of the other.

The circular peripheral edge 3 of the doors and the edge 5 of each adjacent the centre line or vertical diameter are provided with orifices 6 or slots 7 for the insertion of the usual bolts or studs for screwing home the doors when in position and the circumferential periphery may have the usual forcing bolts for pressing off the door from its seat.

Each door is provided with means whereby it may be mounted upon a pair of fixed hinge pins 8 common to both doors mounted upon a support 9 carried by the condenser or other fixed part. These pins 8 are located in the central vertical plane of the condenser or adjacent the vertical centre line or diameter of the unit and preferably above and below the extremities of the vertical diameter.

Each hinge pin has rotatably mounted upon it two eccentric bush or sleeve members 10 and 11 one of which (preferably the outer member 10) may be mounted upon a circular sleeve or concentric part or extension 11^a of the other member 11. The outer ends of the eccentric bush members 10^a and 11^b are provided with means such as orifices 10^a and 11^b for the insertion of tommy bars for the purpose of enabling the eccentric bushes to be rotated about the hinge pins 8.

The doors 1 and 2 may be each provided with a pair of brackets 12 and 13, one located at the upper side and the other located at the lower side of the door. These brackets 12 and 13 are adapted to terminate in rings or housings 12^a and 13^a which are mounted upon the respective eccentric bushes 11 and 10 so that relative rotary movement may be effected between the latter and the housings 12^a and 13^a.

A set screw 14 may be provided in each

of the housings and adapted to co-operate with an arcuate slot 15 in the eccentrics for the purpose of preventing axial movement of the eccentric member and of limiting 5 the rotary movement of the latter.

For the purpose of lubrication, grooves, channels or ducts may be formed in or upon the hinge pins, eccentrics and rings or housings, so that oil or other lubricant may be 10 supplied and distributed upon the working surfaces.

This arrangement of fixed hinge pin, eccentric and housing enables the doors and particularly those parts (such as 1^a and 2^a) 15 adjacent the vertical diameter of the condenser, to be displaced with respect to the axis of the fixed hinge pins 8, so that the part in question may be moved away from its seating 16 to provide clearance in opening up or may be moved towards the seat to diminish the clearance in closing the door.

It will be appreciated that if no displacement of the door adjacent the hinge took 25 place when a door was opened and caused to hinge about the axis of the fixed hinge pin, the inner edge of the door adjacent the axis of movement travelling on the arc of a circle would scrape or rub the surface 30 against it was bedded which would cause a wearing or scraping off of the joining or packing material employed.

Further, it will be observed that when a door was closed under such conditions by 35 moving it about its hinge, a similar scraping action would take place and when the door had been shut it would be impossible to screw up firmly the studs (see Figure 4) to close the door along the edge adjacent 40 the hinge without straining the hinge, as the fixed axis would provide no play or scope for the movement which would be required to permit the tightening of nuts on the securing studs.

45 In operating a structure according to the present invention, the nuts of the securing studs (Figure 4) and the securing or sealing bolts are removed from the holes 6. The forcing off bolts on the circumferential edge 50 are manipulated and at the same time the eccentric bushes 10 corresponding to the door which is to be opened (say, for example, the door 1) are rotated by the operation of a tommy bar or other means. The 55 rotation of the eccentric bushes displaces the edge of the door 1^a adjacent the vertical diameter towards the axis of the fixed pin 8 to a requisite extent to provide the necessary clearance. The door may then be rotated about its eccentric bushes with the usual hinging movement and will swing 60 clear of its seating 16.

In closing, the door is swung to and hinges upon the corresponding eccentric

bushes. When the door has thus been 65 brought approximately into the closed position its eccentrics 12^a are again operated but this time in a manner to cause the part of the door 1^a adjacent the hinge to be moved on to its seating 16. The operation 70 of the eccentrics in this case may be completed as the securing bolts and nuts of the studs are screwed home, so that the required margin of movement is afforded for this 75 purpose.

The construction above described enables the joint between either door and the condenser or seating to be broken independently with facility and without injuring the 80 packing or seating.

Having now described my invention what I claim as new and desire to secure by Letters Patent is:—

1. Closure means for condenser, feed heater and the like units comprising a pair of doors hinged adjacent the vertical centre line of the unit, a pair of fixed pins supported from said unit, a pair of rotatable eccentric bush members mounted around each of the fixed pins, a pair of housing members carried by each door and disposed so that each housing member is acted upon by an eccentric bush member when the latter is rotated so that in opening and closing the doors may be displaced with respect to the 95 unit.

2. Closure means for condenser, feed heater and like units of cylindrical form comprising a pair of doors hinged adjacent the vertical diameter of the unit, a fixed 100 pin supported from said unit and located toward each end of the diameter, a pair of rotatable eccentric members mounted around each fixed pin, one on each pin for one door and another on each pin for the other door, 105 a bracket upon each door adjacent the upper and lower ends of the diameter, a housing member carried by each bracket and adapted to surround the respective eccentric members, whereby each door may be independently moved away from its seating and opened and in independently closing each door may be moved towards its seating.

3. Closure means for condenser, feed heater and the like units of cylindrical form 115 comprising a pair of doors hinged adjacent the vertical diameter of the unit wherein the hinging means are in the form of duplicate sets of members, one set located toward one extremity and the other set at 120 the other extremity of the diameter and each set comprises eccentric means adapted to displace a door away from the unit prior to the opening hinging movement and to displace a door towards the unit after the 125 closing hinging movement.

4. Closure means for condenser, feed heater and the like units of cylindrical form

comprising a pair of doors hinged adjacent to the vertical diameter of the unit wherein the hinging means are in the form of duplicate sets of members, one set located toward 5 one extremity and the other set at the other extremity of the diameter and each set comprises a fixed pin carried by the unit, a sleeve member mounted around the fixed pin and having an eccentric part, a part concentric with the fixed pin and means at its outer end whereby the sleeve may be rotated, a second sleeve member eccentric to the fixed pin mounted around the concentric part of the first sleeve member having 10 means at its outer end whereby it may be rotated, and a housing carried by one door, around each eccentric part of the first sleeve member and a housing carried by the other door, around the second sleeve member 15 whereby the doors may be displaced for the purpose described in opening and closing.

5. Closure means for condenser feed heater and the like units of cylindrical form comprising a pair of doors hinged adjacent to the vertical diameter of the unit wherein the hinging means are in the form of duplicate sets of members, one set located toward one extremity and the other set at the other extremity of the diameter and each set comprises a fixed pin carried by the unit a sleeve member mounted around the fixed pin and having an eccentric part, a part concentric with the fixed pin and means at its outer end whereby the sleeve may be rotated, a second sleeve member eccentric to the fixed pin mounted around the concentric part of the first sleeve member having means at its outer end whereby it may be rotated, and a housing carried by one door 20 around each eccentric part of the first sleeve member and a housing carried by the other door around the second sleeve member, means for preventing axial movement of the sleeve members and means for limiting the 25 rotational movement of the latter, whereby the doors may be displaced for the purpose described in opening and closing.

6. Closure means for condenser feed heater and the like units of cylindrical form comprising a pair of doors hinged adjacent to the vertical diameter of the unit wherein the hinging means are in the form of duplicate sets of members, one set located toward one extremity and the other set at the other extremity of the diameter and each set comprises a fixed pin carried by the unit a sleeve member mounted around the fixed pin and having an eccentric part, a part concentric with the fixed pin and means at its outer end whereby the sleeve may be rotated, a second sleeve member eccentric to the fixed pin mounted around the concentric part of the first sleeve member having means at its outer end whereby it may be rotated, and a housing carried by one door 30 around each eccentric part of the first sleeve member and a housing carried by the other door around the second sleeve member, means for preventing axial movement of the sleeve members and means for limiting the 35 rotational movement of the latter, whereby the doors may be displaced for the purpose described in opening and closing.

7. Closure means for condenser feed heater and like units comprising a pair of doors having peripheral bolt holes and slots and hinged adjacent the centre line of the unit, a pair of fixed pins supported from said unit, a pair of rotatable eccentric bush members mounted around each of the fixed 40 pins, a pair of housing members carried by each door and disposed so that each housing member is acted upon by an eccentric bush member when the latter is rotated so that in opening and closing the doors may 45 be displaced with respect to the unit.

placed for the purpose described in opening and closing.

6. Closure means for condenser, feed heater and the like units of cylindrical form comprising a pair of doors hinged adjacent to the vertical diameter of the unit wherein the hinging means are in the form of duplicate sets of members, one set located toward one extremity and the other set at the other extremity of the diameter and each set comprises a fixed pin carried by the unit a sleeve member mounted around the fixed pin and having an eccentric part, a part concentric with the fixed pin and means at its outer end whereby the sleeve may be rotated, a second sleeve member eccentric to the fixed pin mounted around the concentric part of the first sleeve member having means at its outer end whereby it may be rotated, and a housing carried by one door 50 around each eccentric part of the first sleeve member and a housing carried by the other door around the second sleeve member, means for preventing axial movement of the sleeve members and means for limiting the 55 rotational movement of the latter, whereby the doors may be displaced for the purpose described in opening and closing.

7. Closure means for condenser feed heater and like units comprising a pair of doors having peripheral bolt holes and slots and hinged adjacent the centre line of the unit, a pair of fixed pins supported from said unit, a pair of rotatable eccentric bush members mounted around each of the fixed pins, a pair of housing members carried by each door and disposed so that each housing member is acted upon by an eccentric bush member when the latter is rotated so that in opening and closing the doors may 60 be displaced with respect to the unit.

In testimony whereof I have signed my name to this specification.

JAMES ERNEST JOHNSON.
